US00D746862S

(12) United States Design Patent
Lee et al.

(10) Patent No.: US D746,862 S
(45) Date of Patent:  Jan. 5, 2016

(54) DISPLAY SCREEN OR PORTION THEREOF
WITH ICON

(71) Applicant: Samsung Electronics Co., Ltd.,
Suwon-si (KR)

(72) Inventors: Hyung-Do Lee, Seoul (KR); Hye-Won
Kim, Seoul (KR)

(73) Assignee: Samsung Electronics Co., Ltd.,
Suwon-si (KR)

() Term: 14 Years

(21) Appl. No.: 29/457,677

(22) Filed: Jun. 12, 2013

(51) LOC (10) Cl. 14-14

(52) U.S. Cl.

USPC D14/492

(58) Field of Classification Search

USPC D14/485-495

CPC G06F 3/04817; G06F 3/0482

See application file for complete search history.

(57) CLAIM

The ornamental design for a display screen or portion thereof with icon, as shown and described.

DESCRIPTION

FIG. 1 is a front view of a display screen or portion thereof with icon, showing our new design; and,

FIG. 2 is a front view of a second embodiment thereof. The broken lines represent a boundary and form no part of the claimed design.

1 Claim, 2 Drawing Sheets

FIG. 1

FIG. 2
